UNITED STATES PATENT OFFICE.

PERCY SELWYN NEWBOUND, OF LONDON, ENGLAND.

MANICURING APPLIANCE.

Application filed August 28, 1928, Serial No. 302,452, and in Great Britain September 29, 1927.

This invention relates to manicure appliances, and has for its object to provide a mechanical device for polishing the finger-nails by friction.

5 The appliance of the present invention comprises a rotary buffing member of circular form lined with an elastic pad faced with suitable polishing fabric or material, such as chamois leather for example, and 10 provided with an electric motor whereby it may be caused to revolve about its axis at an appropriate speed.

The rotary buffing member is preferably cup-shaped, the elastic pad extending around 15 its internal periphery; whilst the cup may be revolubly mounted on a support serving to enclose the electric motor. The motor spindle may be geared through frictional or toothed epicyclic gearing to an intermediate driving member to which the buffing member is detachably secured so as to facilitate renewal of the polishing pad. The support may be furnished with a handle which 20 may also carry a switch for controlling the current to the electric motor; or the support may, if desired, be provided with means for enabling it to be clamped to a table or the like when required.

In the accompanying drawings, which 30 illustrate one form of the invention, Figures 1 and 2 are general views of the appliance; Figure 1 being a side elevation partly in section, and Figure 2 a front elevation of the same, also partly in section. Figures 35 3 to 8 show individual elements of the appliance in detail; Figures 3 and 4 being respectively an axial section and a front elevation of the metal frame of the rotary buffing member; whilst Figures 5 and 6 are 40 corresponding views of the intermediate driving member; and Figures 7 and 8 are, again, corresponding views of one of the friction rollers of the epicyclic friction gearing.

45 In the example illustrated, the rotary buffing member A (see Figures 3 and 4) comprises a frame of circular form, spun or pressed to shape from a single blank of thin sheet metal so as to present at its outer or front end a cup-shaped portion 11 having

an externally retroverted marginal flange 12, and towards its inner or rear end a cylindrical neck portion 13 closed at the rear, except around the centre, by a flat disc portion 14 which is stiffened by the central portion 55 being forwardly returned to constitute a substantially cylindrical tube 15, whilst between the cup 11 and neck 12 is formed a circumferential corrugation 16 which is inwardly concave. In the flat disc portion 60 14 are provided three equidistant double-ended arcuate bayonet slots 17 for a purpose hereinafter explained.

The intermediate driving member B (see Figures 5 and 6) comprises a frame of circular form, spun or pressed to shape from a single blank of thin sheet metal so as to present at the rear a disc portion 18 whereof the margin is forwardly returned at 19 and contracted at 20 to constitute a cylindrical 65 socket adapted to receive, and to fit friction-tight about, the cylindrical neck portion 13 of the rotary buffing member. In the rear of the cylindrical socket 20 the driving member presents a circumferentially enlarged and 70 peripherally milled annulus 21 whereby it may be grasped for insertion in or removal from operative position in the external casing when required. The disc portion 18 75 is centrally apertured to carry a metal bearing block 22 for a journal 23 on the outer or front end of the armature spindle of the electric motor (Figure 1); this bearing block, which is riveted in position, being provided with a bush 24 of oiled felt held in position 80 by an annular plug 25 of indiarubber. Riveted to the disc portion 18 so as to project rearwardly therefrom are three equidistant studs 26 whereof the forwardly projecting heads 27 are adapted to pass through the enlarged central openings of the respective bayonet-slots 17 in the buffing member A, and thereafter to hold the latter securely locked to the intermediate member B in whichever direction the latter may be rotated by the 85 electric motor.

The rear portion 19 of the member B enters, and virtually closes, a circular aperture at the front of the relatively stationary casing C wherein the electric motor is 100

mounted; this casing, which is formed of thin sheet metal and is preferably cylindrical throughout with its rear end 28 closed as indicated in Figure 1, having in any event 5 its front portion inwardly cylindrical as at 29 and stiffened as by an outwardly projecting corrugation or flange 30. The studs 26 of the intermediate driving member B carry, in rear of the disc portion 18 of 10 said member, as many friction wheels D (see Figures 7 and 8) each of which is provided with an india-rubber tyre 31 of such effective diameter as to be adapted to fit tightly between the inner periphery of the 15 cylindrical portion 29 of the casing C and a cylindrical portion 32 of the armature spindle, this portion 32 being immediately in rear of the journal 23. As shown, each wheel D consists of a pair of metal discs 33, 34 clipped 20 together as at 35 so as to hold the tyre 31 securely upon their conjointly-presented cylindrical rim portion; the discs being centrally apertured at 36 to revolve upon one of the studs 26; whilst lubrication is provided 25 by a bush 37 of oiled felt held in position between the discs 33, 34 as shown in Figure 7. It will thus be seen that, as the armature spindle 32, 23 revolves, it will cause the 30 wheels D to roll in contact with the cylindrical portion 29 of the casing C, and, through the studs 26, will impart rotation to the intermediate driving member B which in turn will carry round with it the buffing member A.

35 This buffing member A carries an elastic polishing pad (see Figure 1) comprising an annular tube 38 of india rubber which fits within the cup-shaped portion 11 of the member A so as to form an elastic cushion 40 or backing for an annular facing-piece 39 of chamois leather (or other suitable material or fabric). The inner or rear end of the facing-piece 39 is distended, in rear of the cup 11 and cushion 38, by a disc 40 of resilient sheet-material (such as celluloid for example) sprung into position so as to hold the rear margin of the facing-piece tightly within the circumferential corrugation 16 of the member B; whilst the outer or front end 50 of the facing-piece 39, retroverted over the marginal flange 12 of the member B, is in-turned and again retroverted within the annular space 41 between said flange and the outer wall of the cup 11, and secured in 55 said space by means of a metal ring 42 slipped into position from the rear.

It will be seen that the rotary buffing member A, intermediate driving member B, and friction wheels D, can be withdrawn 60 from the casing C by a simple movement parallel to the axis of the armature spindle 32, 23; and that the leather or other facing-piece 39 of the polishing pad can be readily removed from the cup 11 of the 65 member A, by extracting the disc 40 and

ring 42 from their positions, whenever required.

The electric motor E (Figure 1) may be of any suitable type adapted for being housed within the casing C as indicated. In the example illustrated, 43 are screws for securing the motor in position, whilst 44 is a screw-plug of insulating material constituting an abutment for one of the spring-influenced carbon brushes which bear upon the 75 rotary commutator indicated at 45. The casing C is mounted upon a handle F projecting radially from the casing and formed with an axial passage 46 for the flexible leads 47 conveying electric current to the 80 motor. The handle F has a ferrule 52 secured by means of a union nut 49 to a socket 48 projecting radially from the casing C, this socket containing, within a chambered block 50 of insulating material, a spring-influenced snap-over switch of well-known 85 type controlled by a push-piece 51 slidable to-and-fro transversely of the handle F so as to be capable of being readily actuated by the thumb of the operator.

It is to be understood that the structural details described in the foregoing are given only by way of example, and that the actual form and construction of the appliance as a whole may be varied considerably 90 within the limits defined by the subjoined claims.

I claim:

1. A mechanical appliance for polishing the fingernails by friction, comprising an electric motor having a rotary shaft, a rotatable cup-shaped buffing member, a lining for said buffing member consisting of an elastic pad which extends around the inner periphery of said member and is faced with polishing material, and means for connecting said shaft with said buffing member.

2. A mechanical appliance for polishing the fingernails by friction, comprising an electric motor having a rotary shaft, a casing for said motor, a cup-shaped buffing member rotatably mounted on said casing, a lining for said buffing member consisting of an elastic pad which extends around the inner periphery of said member and is faced with polishing material, and means for connecting said shaft with said buffing member.

3. A mechanical appliance for polishing the fingernails by friction, comprising an electric motor having a rotary shaft, a casing for said motor, an intermediate driving member rotatably mounted on said casing, a buffing member of circular form detachably secured to said intermediate driving member, a lining for said buffing member consisting of an elastic pad faced with polishing material, and epicyclic gearing connecting said rotary shaft with said intermediate driving member.

4. A mechanical appliance for polishing the fingernails by friction, comprising an electric motor having a rotary shaft, a casing for said motor, an intermediate driving member rotatably mounted on said casing, a cup shaped buffing member detachably secured to said intermediate driving member, a lining for said buffing member consisting of an elastic pad which extends around the inner periphery of said member and is 10 faced with polishing material, and epicyclic gearing connecting said rotary shaft with said intermediate driving member.

PERCY SELWYN NEWBOUND.
